CLAIM

I claim the ornamental design for a discomfort attenuating device, as shown and described.

DESCRIPTION

FIG. 1 is an isometric top view of a discomfort attenuating device;

FIG. 2 is an isometric bottom view thereof;

FIG. 3 is a top view thereof;

FIG. 4 is a bottom view thereof;

FIG. 5 is a front view thereof;

FIG. 6 is a right side view thereof;

FIG. 7 is a rear view thereof;

FIG. 8 is a left side view thereof;

FIG. 9 is a sectioned elevation left side view thereof, the section being taken in a direction of section line 9-9 of FIG.

3; and,

FIG. 10 is a sectioned elevation left side view thereof, the section being taken in a direction of section line 10-10 of FIG. 3.

The evenly spaced broken lines in the drawings illustrate features that form no part of the claim.
